UNITED STATES PATENT OFFICE.

WILLIAM F. HOCHSPEIER, OF JERSEY CITY, NEW JERSEY, ASSIGNOR OF
ONE-HALF TO JOHN H. GREIF AND LOUIS H. GREIF, OF JERSEY CITY,
NEW JERSEY.

DRAFTING DEVICE.

SPECIFICATION forming part of Letters Patent No. 709,219, dated September 16, 1902.

Application filed January 25, 1902. Serial No. 91,263. (No model.)

To all whom it may concern:

Be it known that I, WILLIAM F. HOCHSPEIER, a citizen of the United States, residing at Jersey City Heights, in the county of 5 Hudson and State of New Jersey, have invented certain new and useful Improvements in Drafting Devices, of which the following is a specification.

This invention relates to certain improvements in a drafting device of that class in which a centrally-pivoted disk provided with 10 openings of different shapes and sizes is moved successively according to a certain predetermined graduation, so as to be used to 15 describe geometrical figures of various designs, said drafting device being devised as an entertaining toy for children, as well as for use in larger sizes for designing ornamental figures for floor-coverings, &c.; and 20 for this purpose the invention consists of a drafting device which comprises a base-plate provided with a center pivot, a rotary disk provided with openings of various shapes, a pointer on said rotary disk, a sheet of drafting-paper interposed between the base-plate and said disk, graduations on the base-plate or disk along which the pointer is moved, and means for fastening the paper to the base-plate while the geometrical figures are drawn 25 30 on the paper by the operator by means of successive movements of the disk; and the invention consists, further, of certain details of construction and combinations of parts, which will be fully described hereinafter and finally 35 pointed out in the claims.

In the accompanying drawings, Figure 1 is an elevation of my improved drafting device. Fig. 2 is a top plan view thereof. Fig. 3 is a vertical transverse section on line 3-3, Fig. 2, 40 and Fig. 4 is a disk showing the geometrical designs made with my improved drafting device.

Similar letters of reference indicate corresponding parts.

Referring to the drawings, A represents the 45 base-plate or block of my improved drafting device, which base-plate may be made of wood, pasteboard, sheet metal, or other suitable material. The base-plate A is provided at its 50 center with a pivot a, which is attached to the

same and which serves for placing thereon a rotary disk D, which latter is provided with a center opening for receiving the pivot-pin a, said disk being provided with a number of round, triangular, or other openings d', which are grouped around the center of the disk, so that the edges thereof serve for guiding the pencil in making the geometrical figures, which represent various combinations formed by said openings as the disk is rotated. The 55 rotary disk D is preferably made of sheet metal; but it can also be made of cardboard, celluloid, or other suitable material. The disk is provided with a pointer that is attached to the same, which pointer projects 60 radially somewhat beyond the circumference of the disk, so as to be set along the subdivisions of a graduated circle a', that is marked on the base-plate A, said circle being concentric with the axis of the pivot-pin a. 70

Interposed between the base-plate A and the rotary disk D is a sheet of paper B, which is provided with a central perforation, so as to fit over the pin a, which sheet of paper is preferably of larger size than the rotating 75 disk and of smaller size than the graduated circle. This paper disk is placed on the pivot-pin and held in position on the base-plate by being placed on one or more pointed pins e, which project upwardly from the base-plate 80 and serve to hold the paper disk firmly in position while the disk D is moved successively over the same. A large variety of geometrical figures can be drawn on the interposed disk of paper by tracing a pencil along the 85 edge of the openings d' and by moving the rotary disk D step by step from one subdivision of the graduated circle a' to another. When the rotary disk D has been moved through one entire rotation, so that its index 90 arrives at the starting-point, the geometrical figure that is desired to be drawn on the paper disk is completed, similar to that shown in Fig. 3, which shows one geometrical design drawn by my improved device. 95

My improved drafting device is intended to furnish a complete article for drawing geometrical and other figures—that is to say, it is intended to be furnished complete with a number of paper disks—so that by inserting 100

a paper disk the device is ready for use. In this form the device provides a very entertaining toy for children, as it teaches a knowledge of geometrical designs while using the same. When the paper disks are exhausted and other paper is to be used, it is necessary to cut a central opening in the paper, so as to fit over the center pin of the base-plate, and in this case the pencil may be passed through d^2 at the end of the pointer, so as to describe a circle around the geometrical design made by the device, said circle enabling the user to cut the paper into disk form. Large sizes of the device can be made for use in making diagrams to be used in the manufacture of oil-cloth and other floor-coverings, wall-papers, &c. In this case it is preferable to make the device on a larger scale, and the disk is also preferably made of celluloid or other suitable material, so as to permit the observation of the drawing of the design.

I am aware that devices for laying out geometrical figures have heretofore been patented in which a plotting-disk provided with openings of different shapes are used, and therefore I do not desire to claim the same broadly.

Having thus described my invention, I claim as new and desire to secure by Letters

30 Patent—

1. A device for drafting geometrical figures, consisting of a base-plate provided with a center pin and pointed pins equidistant from said center pin, a rotary disk provided with a center opening and with openings of different sizes and shapes in the body of the disk, a pointer on said disk, and a graduated circle

arranged on said base-plate beyond the edge of said disk, substantially as set forth.

2. A device for drafting geometrical figures, 40 consisting of a base-plate provided with a center pin and a circle concentric with the axis of said pin, a rotary disk provided with a projecting index at one point of said disk and with openings of different sizes and shapes, 45 and a plurality of pins projecting upwardly from said base-plate, substantially as set forth.

3. A device for drafting geometrical figures, 50 consisting of a base-plate provided with a projecting center pin, a plurality of pins provided on the surface of said base-plate, a graduated circle concentric with the axis of the center pin, and a rotary disk provided with a pointer at one point of its circumference 55 and with a number of openings of different sizes and shapes, substantially as set forth.

4. A device for drafting geometrical figures, 60 consisting of a base-plate provided with a graduated circle, a centrally-guided disk provided with plotting-openings of different sizes and shapes, a pointer on said disk adapted to move with the disk along the graduated circle, and means for holding a sheet of paper 65 stationary on the base-plate, substantially as set forth.

In testimony that I claim the foregoing as my invention I have signed my name in presence of two subscribing witnesses.

WILLIAM F. HOCHSPEIER.
